(57) **CLAIM**

The ornamental design for a speaker system for bath and shower environments as shown and described.

DESCRIPTION

FIG. 1 is a perspective view of a speaker system for bath and shower environments, showing our new design;

FIG. 2 is a front view of the claimed design shown in FIG. 1;

FIG. 3 is a rear view of the claimed design shown in FIG. 1;

FIG. 4 is a side view of the claimed design shown in FIG. 1;

FIG. 5 is another side view of the claimed design shown in FIG. 1;

FIG. 6 is a top view of the claimed design shown in FIG. 1; and,

FIG. 7 is a bottom view of the claimed design shown in FIG. 1.

The dash-dot broken lines immediately adjacent the shaded areas represent the bounds of the claimed design while all other broken lines are included for the purpose of illustrating portions of the speaker system for bath and shower environments; the broken lines form no part of the claimed design.
